UNITED STATES PATENT OFFICE.

WEBB C. SWEET, OF PHILADELPHIA, PENNSYLVANIA.

DESIGN FOR A VEHICLE-TOP.

54,700.

Specification for Design.

Patented Mar. 9, 1920.

Application filed September 14, 1917. Serial No. 191,478. Term of patent 7 years.

To all whom it may concern:

Be it known that I, WEBB C. SWEET, a citizen of the United States of America, residing at Philadelphia, in the county of Philadelphia and State of Pennsylvania, have invented a new, original, and ornamental Design for Vehicle-Tops, of which the following is a specification, reference being had to the accompanying drawing, forming part thereof.

Figure 1 is a side elevational view of my design; and

Fig. 2 is a rear view thereof.

I claim:

The ornamental design for a vehicle top as shown.

WEBB C. SWEET.
